UNITED STATES PATENT OFFICE

JAMES F. HUGHES, OF NEW YORK, N. Y.

MOUTHPIECE FOR CIGARETTES

Application filed February 18, 1932. Serial No. 593,846.

The present invention relates to mouthpieces for cigars and cigarettes and consists in the combinations and arrangements of elements hereinafter described and particularly set forth in the accompanying claims.

The purpose of the invention is to provide a device which will keep the cigarette dry and effectively prevent the nicotine and tobacco fibres from entering the mouth and which will not offer any inconvenience or hindrance to the pleasure of smoking. The article is furthermore of the utmost simplicity and in its use is absolutely concealed from view.

A further object is in having the article of such structure that it may be incorporated into the body of the cigarette or cigar during manufacture, or may equally well be designed as a separate and independent device to be conveniently applied to the cigarette at the time of smoking.

The devices shown herein are proposed as further improvements over the similar articles disclosed in my co-pending applications for U. S. Letters Patent, and issued U. S. patents, to wit:

“Attachment for cigarette” Patent No. 1,821,159; Sept. 1, 1931.

“Mouthpiece for cigarettes” Patent No. 1,821,160; Sept. 1, 1931.

“Mouthpiece for cigarettes” Serial No. 469,168; filed July 19, 1930.

“Attachment for cigarette” Serial No. 501,446; filed Dec. 10, 1930.

“Mouthpiece for cigarettes” Serial No. 538,379; filed May 18, 1931.

“Mouthpiece for cigarettes” Patent No. 1,841,952; Jan. 20, 1932.

The invention is shown by way of illustration in the accompanying drawing, wherein:

Figure 1 is a perspective view showing a cigarette with the article attached.

Figure 2 an end elevational view thereof.

Figure 3 a detailed perspective view illustrating the manner of applying the article.

Figure 4 shows the blank from which the article is formed.

Figure 5 shows a modified construction of the device.

Figures 6 and 7 are views corresponding to Figures 3 and 4 above.

Figure 8 shows another modified construction, and

Figures 9, 10 and 11 are views showing a further modified construction and correspond to Figures 5, 6 and 7 above.

Referring to the construction in further detail, and wherein the same reference characters designate corresponding parts in the different figures, 15 represents an ordinary cigarette to the end 16 of which is adapted to be attached the article shown herein.

This end of the cigarette is in no way altered whether the device be incorporated in the cigarette when made or applied thereto as a separate attachment. The article may be of large or small size accordingly as the smoker desires to puff lightly or inhale deeply and fully, as will be understood.

The device per se consists of a thin piece of paper 17 having one side edge notched or serrated to provide a plurality of tabs or flaps 18 and said strip is adapted to be wrapped once around the end 16 of the cigarette and suitably secured by adhesive around the end edge 19 as shown.

The several flaps or tabs 18 are folded inwardly and against the tobacco at the end of the cigarette as shown in Figure 1 and provide a central orifice or opening 20 through which smoke passes as will be understood. In their inturned or applied position as in Figures 1 and 2 said flaps are held lightly together by their over-lapping side portions by suitable adhesive.

In the construction shown in Figures 5, 6 and 7 the strip 22 is formed with a plurality of apertures 23 notched as at 24 providing the several flaps or tabs 25 that are folded inwardly and against the tobacco as shown in Figure 5. In this relation the apertures 23 and the central opening 26 permit the smoke to pass freely into the mouth though prevent the tobacco fibres from doing so.

In the arrangement shown in Figure 8 the construction is similar to that in Figures 5, 6 and 7 and in this instance the several apertures 27 are located just at the edge of the cigarette wrapper while in Figure 5 said

apertures are located slightly inwardly of said edge.

In the arrangement shown in Figure 9, 5 10 and 11 the paper strip 28 is formed with tabs 29 having rounded edges as distinct from the straight and squared edges shown in Figure 4, and in this instance there is a small aperture 30 formed in each tab. Said apertures 30 and the central opening 31 provide 10 for the free passage of smoke and prevent the passage of tobacco fibres as will be understood.

It is to be understood the invention is not 15 limited to the details of construction here shown and described, as these may be varied widely without departing from the scope of the invention as defined by the claims.

What is claimed as new is:

1. A mouthpiece for a cigarette, comprising 20 a paper strip adapted to encircle the cigarette end and having tabs adapted to be bent into contact with the tobacco of the cigarette, the tabs when bent having their side edges in overlapping relation and having an annular series of openings for the passage of smoke, and the tabs being adapted when bent to have their free ends arranged in slightly spaced relation to provide an opening concentrically related to said annular series of 25 openings and also providing for the passage of smoke.

2. A mouthpiece for a cigarette, comprising a paper strip adapted to encircle the cigarette end and having tabs adapted to be bent into contact with the tobacco of the cigarette, the tabs being adapted when bent 70 to have their side edges arranged in overlapping relation and to have their free ends arranged in slightly spaced relation to provide an opening for the passage of smoke, and the tabs being provided in their side edges 75 with notches which when the tabs are bent provide an annular series of openings surrounding said first opening and also providing for the passage of smoke.

3. A mouthpiece for a cigarette, comprising 80 a paper strip adapted to encircle the cigarette end and having tabs adapted to be bent into contact with the tobacco of the cigarette, the tabs being adapted when bent 85 to have their side edges arranged in overlapping relation and to have their free ends arranged in slightly spaced relation to provide an opening for the passage of smoke, and the tabs being provided in their side edges 90 with notches which when the tabs are bent provide an annular series of openings each extending across the edge of the cigarette and also providing for the passage of smoke.

In testimony whereof, I affix my signature. 95

JAMES F. HUGHES.
